UNITED STATES PATENT OFFICE.

FREDERICK WILLIAM HALL, OF LONDON, ENGLAND.

DESIGN FOR A COMBINED STREET-PILLAR AND STAMP-VENDING-MACHINE CASE.

49,819.

Specification for Design.

Patented Oct. 31, 1916.

Application filed June 21, 1916. Serial No. 105,076. Term of patent 7 years.

To all whom it may concern:

Be it known that I, FREDERICK WILLIAM HALL, a subject of the King of Great Britain and Ireland, residing at 45 Carlisle Mansions, Victoria street, S. W., London, England, have invented a new, original, and ornamental Design for Combined Street-Pillars and Stamp-Vending-Machine Cases, of which the following is a specification, reference being had to the accompanying drawing, forming part thereof.

Figure 1 is a front elevation of a combined street pillar and stamp vending machine case showing my new design, and Fig. 2 is a section on line A—B of Fig. 1.

I claim—

The ornamental design for a combined street pillar and stamp vending machine case as shown.

FREDERICK WILLIAM HALL.
